UNITED STATES PATENT OFFICE

2,110,681

PACKING BOX OR CARTON

Robert E. Rutledge, Kalamazoo, Mich., assignor
to Sutherland Paper Company, Kalamazoo,
Mich., a corporation of Michigan

Application March 7, 1935, Serial No. 9,703

2 Claims. (Cl. 229—16)

The main objects of this invention are:

First, to provide an improved packing box or carton which is especially well adapted for the merchandising of small fruits and vegetables.

Second, to provide a container of the foregoing character which is simple and economical in its parts and very easy to pack.

Objects relating to details and economies of my invention will appear from the description to follow. The invention is defined and pointed out in the claims. A structure which is a preferred embodiment of my invention is illustrated in the accompanying drawings, in which:

Fig. 1 is a perspective view of a packing box or carton embodying features of my invention.

Fig. 2 is a top plan view of the carton blank in the flat.

Fig. 3 is a top plan view of the carton in inverted position showing the inner bottom closure flaps interconnected and the outer bottom closure flaps open.

Fig. 4 is a top plan view of the carton in inverted position showing the inner bottom closure flaps closed.

Fig. 5 is a view mainly in vertical section through the box and a packing apparatus and packed box prior to removing the box, the discharging of the parts being indicated by dotted lines.

Fig. 6 is a perspective view of the box and packing apparatus in packing position.

Fig. 7 is a perspective view of a modification having perpendicular side walls, the carton being shown in another type of packing form suitable for a straight side carton.

Fig. 8 is a view in transverse section taken on a line corresponding to line 8—8 of Fig. 7.

Fig. 9 is a top plan view of the modified carton blank in the flat.

Fig. 10 is a perspective view of the modified packing form.

The embodiment of my improved packing box or carton illustrated in Figs. 1 to 6 inclusive comprises an integral blank 1 which is cut, scored and folded to provide a square central top member 2 having a window opening 3 adapted to expose the contents of the box for inspection. If desired, the window opening may be provided with a closure pane or panel of transparent material (not shown). Downwardly and inwardly extending tapered side walls 4 and 5 are connected to the opposite edges of the top member.

Side wall flaps 6 are connected to the opposite edges of the side walls 4 at the corners of the box, the flaps 6 being arranged in overlapping rela-

tion with the inner sides of the side walls 5. From the lower edges of the side walls 4 and 5 extend inwardly tapered bottom flaps 7 and 8 which are adapted to be connected in overlapping pairs to provide a bottom closure 9 for the box. In this way my box or carton is made up of one piece of material, preferably container or box board.

The inner bottom flaps 7 are adapted to be interconnected first, as shown by Fig. 3, these flaps being provided with opposed interlocking tongues and slits, the slits 10 being disposed parallel to the line of connection between their bottom flaps and the side walls. After the inner bottom flaps 7 are interconnected, the outer, bottom flaps 8 are closed and interlocked by inserting the tongue 11 through the slot 12, this connection preferably being provided with transverse locking means comprising the offset 13 in the slot 12. The arrangement is such that the recess 14 at the base of the tongue 11 is held in engaged position with the flap 8 at the end of the slot 12. This locking means prevents the bottom flaps from opening even when supporting the contents of the carton.

It will be observed that the bottom closure flaps 7 and 8 provide a reinforced or double bottom closure for the box although the blank 1 consists of but one piece. Further, the bottom closure flaps 7 and 8 are readily closed and interconnected after the box has been packed in inverted position. While the carton or box may be packed without any packing apparatus at all, I prefer to use the packing apparatus of the character disclosed and claimed in Patent 1,950,961, dated March 13, 1934, to William F. Allen.

As shown by Figs. 5 and 6, such packing apparatus comprises a substantially rectangular frame 15 having side walls 16 hinged thereto and a facing plate 17 arranged within and vertically movable relative to the side walls. The side walls of the packing apparatus have inwardly projecting flanges 18 coacting with the facing plate 17 in such manner that the side walls are swung inwardly to support the side walls of the box 19 when the latter is inserted in inverted position in the packing apparatus.

The side walls 16 have central vertical slots 20 for the passage of a pair of opposed handles 21 and a pair of T-shaped tongues 22 connected to 50 the facing plate 17.

In packing, the carton blank 1 is partially set up as shown by Fig. 6 and inserted within the packing apparatus 23 in inverted position with the bottom closure flaps 7 and 8 open as shown. 55

The facing layer 24 of the contents 25 is then placed in the carton, and after this the remainder of the contents is poured into the inverted carton to fill the same. The bottom closure flaps are then closed and interconnected while the box is still in inverted packing position. When the packing is completed, the packed container is discharged from the packing apparatus and inverted by shifting the handles 21, as illustrated in Fig. 5.

Referring to Figs. 7 to 10 inclusive of the drawings, 26 is a packing form preferably of metal, comprising a bottom 27 and upright substantially triangular side walls 28, having outwardly turned upper end portions 29 providing finger pieces. The form is adapted to receive the carton 30 having substantially perpendicular side walls 31 connected to the member 32.

The packing box or carton 30 comprises an integral blank 33 which is cut, scored and folded in the manner described above in connection with the blank 1. The blank is set up and disposed in inverted position in the packing form 28 and packed. The top layer of small vegetables, such as for instance as Brussels sprouts or berries, or whatever commodity is packed therein, is faced in a uniform manner, the bottom of the box remaining open until after it is packed, the bottom being then closed by interlocking the opposing flaps 34 and 35, as pointed out above in connection with Figs. 1 to 6 inclusive.

In the case of certain commodities, it is desirable to cover the opening 36 in the top member 32 with a transparent window pane. "Cellophane" is preferred, the sheet being placed on the top member within the carton before packing the first or facing layer, or it may be secured in place by suitable adhesive.

From the foregoing it will be appreciated by those skilled in the art that I provide a packing box or carton which is economical to manufacture and very easy to pack. The package is highly desirable for merchandising small fruits and vegetables such as Brussels sprouts and the like, although baked goods and various other products may be sold therein. The closed package is strong and durable and not likely to open when filled although made of but one piece of material.

I have illustrated and described my improvements in an embodiment which I have found very practical. I have not attempted to illustrate or describe other embodiments or adaptations as it is believed this disclosure will enable those skilled in the art to embody or adapt my improvements as may be desired.

Although I have shown and described a cer-

tain specific embodiment of my invention, I am fully aware that many modifications thereof are possible. My invention is therefore not to be restricted except insofar as is necessitated by the prior art and by the spirit of the appended claims. 5

Having thus described my invention what I claim as new and desire to secure by Letters Patent is:

1. A packing box comprising an integral blank cut, scored and folded to provide a central top member having a window opening, side walls connected to the edges of said top member, side wall flaps connected to the opposite edges of a pair of said side walls at the corners of the box and being arranged in overlapping relation to 10 and within the inner sides of the other pair of side walls, the flaps overlapping a given one of said other pair being mutually unconnected, and bottom forming flaps extending inwardly from the lower edges of said side walls and being interconnected in pairs to provide a closure for the 15 bottom of the box, the bottom flaps of said first named pair of side walls having identical opposed interlocking tongues and slits, the slits being disposed parallel to the line of connection 20 between their bottom flaps and the side walls, the bottom flaps of said second named pair of side walls having a tongue and slot connection provided with transverse locking means, said first named bottom flaps being arranged in overlapping relation with and within said last named 25 bottom flaps.

2. A packing box comprising an integral blank provided with a central top member having a window opening, downwardly and inwardly extending tapered side walls connected to the edges of said top member, side wall flaps connected to the opposite edges of a pair of said side walls at the corners of the box and being arranged in overlapping relation to 30 and within the inner sides of the other pair of side walls, and inwardly tapered bottom forming flaps extending inwardly from the lower edges of said side walls and being interconnected in pairs to provide a closure for the bottom of the box, the bottom flaps of said first named pair of side walls having opposed similar interlocking tongues and slits, the slits being disposed parallel to the line of connection 35 between their bottom flaps and the side walls, the bottom flaps of said second named pair of side walls having a tongue and slot connection provided with transverse locking means, said first named bottom flaps being arranged in overlapping relation with and within said last named bottom flaps. 50

ROBERT E. RUTLEDGE. 55
